2,358,680

MACHINE FOR FILLING CANS

Harry D. Ayars, Philadelphia, Pa., assignor to
 Continental Can Company, Inc., New York,
 N. Y., a corporation of New York

Original application January 4, 1943, Serial No.
 471,272. Divided and this application Decem-
 ber 30, 1943, Serial No. 516,280

3 Claims. (Cl. 222—168)

In my co-pending application Serial No. 471,272, filed January 4, 1943, there is shown and described a machine for filling cans which embodies a tank which is rotated, and associated with the tank are measuring pockets which are filled by the tank, and which discharge a measured quantity of liquid product into a container. Disposed in the tank is a control plate for covering the openings leading to the measuring compartments.

The present application is a division of the application referred to, and is directed particularly to the control plate and the manner of mounting the same, which controls the flow of the liquid product from the tank into the measuring pockets.

An object of the invention is to provide a supporting means for the control plate which permits said plate to freely rest on the bottom of the tank, but is held from rotation with the tank.

A further object of the invention is to provide a supporting means for the control plate so that it may be readily removed for cleaning purposes and replaced, without the necessity of releasing any securing means therefor.

In the drawings, Figure 1 is a view in vertical section showing a portion of a filling machine embodying my improvement.

Figure 2 is a plan view of the control plate and the bottom of the tank showing the relation of the control plate to the openings leading to the measuring pockets.

The can filling machine to which the improvement has been applied includes a center supporting column 1, which may be of any suitable construction. This column is mounted on a base 2. Mounted on this column is a sleeve 3 to which is attached a tank 4. Secured to the tank and depending therefrom are a series of measuring units, one of which is shown in section in Figure 1. The measuring unit includes an upper section 5 and a lower section 6. These two sections have a telescoping connection and a suitable sealing gland 7 provides a liquid tight connection between the two sections. Extending laterally from the column 1 is a spider bracket 8. The lower section of the measuring pocket is bolted to this spider bracket 8. Secured to the lower end of the telescoping section 6 is a valve housing 9 having discharge ports 10 which are controlled by the rotary valve 11. This valve mechanism is shown, described and claimed in my co-pending application Serial

No. 471,272, and further description thereof is not thought necessary.

Mounted on the base 2 is a can support 12 along which the cans to be filled are moved. The can is shown in broken lines at C, in Figure 1. The cans are placed beneath each measuring pocket and the contents of the measuring pocket is discharged into the can during a portion of the rotation of the machine.

10 Located in the tank 3 is a spider bracket 13. Said spider bracket is provided with a plurality of arms, two of which are shown in Figure 2. These spider arms project radially from the center of the tank. They are secured to a sleeve 14 mounted at the upper end of the stationary column 1. These arms do not contact with the bottom of the tank. At the outer end of each arm is an upstanding pin 15 the upper end of which is tapered, as indicated at 16. The bottom of the tank is provided with a plurality of openings 17. These openings are covered during a portion of the rotation of the tank by a control plate 18. This control plate is arcuate and is provided with laterally projecting lugs 19 which engage over the pins 15. The plate rests on the bottom of the tank and the pins prevent the plate from rotating with the tank. In the bottom of the plate is an arcuate channel 20 which, as shown in broken lines in Fig. 2, terminates short of the end of the plate.

30 There is a pipe 21 secured to the plate which extends upwardly therefrom. This pipe is connected to the channel. The pipe extends above the normal level of the liquid product in the tank and serves as a venting means for the emptying of the measuring pockets.

35 As noted above, this cutoff plate extends only through a segment of the arc of a circle of the filling machine. When the openings 17 move out 40 from underneath the plate, then the liquid product in the tank will fill the measuring pocket. At this time the valve is closed. After the pocket is filled, then the opening leading to the tank passes beneath the plate and this will cover the opening. 45 When the opening reaches the channel in the under face of the plate then the pocket is connected through the pipe 21 to the atmosphere so that when the valve is open, the liquid product in the measuring pocket will pass freely into the receptacle therebeneath. The plate rests on the bottom of the tank and is held pressed against the bottom by gravity. Under these conditions, a film of the filling product will form beneath the plate and this facilitates the movement of the 50 tank relative to the plate which is stationary, and

at the same time a perfect seal is maintained between the tank and the measuring pocket, at the time of emptying of the pockets.

When it is desired to clean the machine the control plate can be readily lifted from the tank as it is only attached to the spider arms 13 by the projection of the pins through the openings in the lugs carried by said control plate. The plate is lifted off the pins and removed from the tank and after cleaning, it can be placed back in the tank and the lugs will slip freely over the pins.

It is obvious that many changes may be made in the details of construction of this supporting means for the control plate without departing from the spirit of the invention as set forth in the appended claims.

I claim:

1. In a filling machine, a rotatable tank having a plurality of discharge openings arranged concentrically of the center of the tank, a measuring pocket associated with each opening, a valve mechanism at the lower end of each pocket for controlling the discharge of the contents of the pocket, a segmental cutoff plate disposed in said tank so as to cover a portion of the openings leading to the measuring pockets, and means for preventing the cutoff plate from rotating with the tank while permitting said cutoff plate to move freely vertically.

2. In a filling machine, a rotatable tank having a plurality of discharge openings arranged concentrically of the center of the tank, a measuring

pocket associated with each opening, a valve mechanism at the lower end of each pocket for controlling the discharge of the contents of the pocket, a segmental cutoff plate disposed in said tank so as to cover a portion of the openings leading to the measuring pockets, and means for preventing the cutoff plate from rotating with the tank while permitting said cutoff plate to move freely vertically, said cutoff plate having an ar-
10 cuate recess in the under face thereof terminating short of the ends of the plate and a venting pipe carried by said cutoff plate and connected to said recess, said venting pipe extending upwardly above the surface of the liquid product in the tank.

3. In a filling machine, a rotatable tank having a plurality of discharge openings arranged concentrically of the center of the tank, a measuring pocket associated with each opening, a valve mechanism at the lower end of each pocket for controlling the discharge of the contents of the pocket, a stationary spider bracket disposed in said tank, upwardly projecting pins carried by said spider bracket, a segmental cutoff plate disposed in said tank so as to cover a portion of the openings leading to the measuring pockets, said cutoff plate having projecting lugs provided with openings adapted to fit over said pins, said lugs being disposed a slight distance above the spider bracket so that the plate rests on the bottom of the tank and is held in contact therewith by gravity.

HARRY D. AYARS.
